UNITED STATES PATENT OFFICE.

HERMAN C. WELTER AND CHARLES E. HALL, OF ROCHESTER, NEW YORK, ASSIGNEES
TO HALL-WELTER COMPANY, INC., OF ATTICA, NEW YORK.

CHECKWRITER.

1,187,403.

Specification of Letters Patent. Patented June 13, 1916.

Application filed May 3, 1915. Serial No. 25,578.

To all whom it may concern:

Be it known that we, HERMAN C. WELTER and CHARLES E. HALL, citizens of the United States, residing at Rochester, in the county 6 of Monroe and State of New York, have invented certain new and useful Improvements in Checkwriters, of which the following is a specification.

The object of this invention is to provide 10 a new and improved form of check writer.

Another object of the invention is to provide 15 a new and improved form of feed for the check on which the check writer is operating.

Another object of the invention is to increase 15 the capacity of the check writer for characters and figures with which to mark checks.

These and other objects of the invention 20 will be fully illustrated in the drawings, described in the specification and pointed out in the claims at the end thereof.

In the drawings, Figure 1 is a top plan view of the improved check writer. Fig. 2 25 is a vertical longitudinal section on the line 2^x—2^x of Fig. 1. Fig. 3 is a top plan view of the machine with the casing removed. Fig. 4 is a detail view of the ratchet feeding mechanism. Fig. 5 is a detail view of the 30 paper feeding device. Fig. 6 is a detail view of the gearing for driving the machine. Fig. 7 is a top plan view of the platen. Fig. 8 is a vertical section through the platen on the line 8^x—8^x of Fig. 8. Fig. 9 is a detail 35 view of a portion of the type bar belt. Fig. 10 is a detail view of a portion of the type bar belt the parts being shown on a large scale. Fig. 11 is a detail perspective view of a portion of the cover and the pointer or indicator. Fig. 12 is a detail view of the 40 bracket 12.

In the drawings like reference numerals indicate like characters.

In the drawings reference numeral 1 indicates 45 the base on which the machine is built. On the base is the platform or bed plate 2 and on top of this bed plate a portion of the mechanism is carried and the balance of the mechanism is carried below the bed plate inside 50 of the base. Supported on the platform 2 are the brackets 3 and 4. In these brackets is supported for oscillation the shaft 5, the end of which projects laterally from the machine, on which is keyed the crank 6 to

which is fastened a handle 7 by which the 55 machine is operated.

On top of the bracket 3 is supported the auxiliary bracket 8. On this bracket is supported a shaft 9 which carries a sprocket wheel 10. At the opposite end of the machine the brackets 11 and 12 are supported on the bed plate. On the bracket 11 is supported a shaft 13 which carries a sprocket wheel 14. Between the sprocket wheels 10 and 14 travels a sprocket chain 15. To provide for adjustment of this chain the auxiliary bracket 8 which supports the shaft 9 is made adjustable on the bracket 3 in the manner that will now be described.

The bracket 8 is slotted at 16 and the 70 bracket 3 is slotted at 17. Through these slots extend the screws 18 and 19, the screw 18 making threaded engagement with the bracket 3 and the screw 19 making threaded engagement with the bracket 8. By loosening these screws the bracket 8 is released for adjustment along the bracket 3 and by tightening them it is clamped in the desired position. 75

The shaft 13 extends through the bracket 80 11 and has keyed on the opposite end thereof the pinion 20, which pinion meshes with the pinion 21 carried on the stud 22 mounted in the bracket 11. The pinion 21 is an idler and in turn meshes with the pinion 23 85 mounted on the shaft 24, which shaft extends through the brackets 11 and 12. On this shaft 24 is keyed the drum 25 and the locking wheel 26. Mounted between the brackets 11 and 12 is a shaft 27 on which is 90 keyed the drum 28. Around the drums 25 and 28 passes the type belt, which belt is made up preferably of two flexible steel bands 29, between which is mounted a series of bars, 100, each of which bars carries 95 a type plate thereon, each of the type plates having different characters thereon, the characters being varied according to what the machine is intended to print on the checks. 100

The drums 25 and 28 are provided on their peripheries with longitudinally extending grooves spaced equal distances apart and adapted to receive corresponding projections 101, preferably V-shape, formed 105 on the under side of the type bars 100. Each of these type bars 100 extends between and is removably secured to the bands

29 at points in its center line and is tapered each side of such fastenings to permit the projection 101 thereon being properly seated when in engagement with a groove in 5 one of the drums. Such a construction of the type bars prevents a buckling of the bands and permits the selected type bar to become properly centered when engaged by the platen 30. The projections 101 and their 10 cooperating grooves in the drums also provide means for properly advancing the type bars and for rotating the drum 28.

Movably mounted in the base of the machine is the platen 30, which platen may be 15 provided with either a serrated or a smooth surface. This plate is driven against the type bar that is positioned opposite thereto for the purpose of causing the type bar to make an impression on the check which 20 has been interposed between the platen and the type bar. The platen is moved to secure this result by a mechanism which we will now describe.

Mounted in the base of the machine is a 25 stud 31 on which is pivotally mounted a lever 32, one end of which lever carries the platen 30. To the opposite end of the lever is connected a spring 33 by which that end of the lever is normally held up and 30 the opposite end of the lever is normally held down. Fastened to the lever 32 is a bracket 34, screws 35 and 36 being provided for the purpose of making the connection between the two parts, although the parts 35 may be fastened together by rivets instead. The bracket 34 has a large opening 37 therein through which extends the link 38, which link is carried on the end of a crank 39, which crank is keyed to the shaft 5. The 40 crank 39 and link 38 form a toggle by which the movement of the handle 7 and shaft 5 is communicated to the lever 32. The thrust of the link 38 is communicated to the bracket 34 and lever 32 by means of lock 45 nuts 40 and 41 which are threaded on the link 38 and which may be set thereon to hold or bring the lever 32 and platen 30 to the desired position in contact with the type bar with the desired pressure when the parts 50 are in the position shown in Fig. 2.

Keyed to the shaft 5 is a cam 42. On the bracket 4 is a lug 43 in which is mounted a stud 44 on which is pivotally mounted a lever 45 having an antifriction roller 46 at 55 the upper end thereof, which roller makes contact with the cam 42. As the shaft 5 operates and the cam 43 rocks with it, the lever 45 will be oscillated in turn. Fas- 60 tened to the bed plate of the machine is a bracket 47 having upturned ends 48 and 49, which ends are slotted and in which slotted ends is mounted to slide a locking pin 50. The forward end of this pin is pointed to engage between the teeth of the locking 65 wheel 26 and the rear end of the pin is

pivotaly connected to the lever 45. The lever 45 and pin 50 are fastened together by the stud 51. A spring 52 is provided fastened at one end to a lug 53 provided on the case therefor and fastened at its other end to the stud 51. By this spring the pin 50 is normally held out of engagement from the locking wheel 26 and the anti-friction roller is held in engagement with the cam 42. As the shaft 5 oscillates the 70 cam 42 oscillates with it and rocks the lever 45 and drives the pin 50 into locking engagement between the teeth of the locking wheel and centers the locking wheel and drum and type bar with reference to the 75 platen and holds the parts in their position while the platen moves to complete the work of printing or embossing or punching the check.

Mounted in the base of the machine are 80 the brackets 54 and 55 in which brackets is mounted to rotate the shaft 56. At one end of the shaft 56 is provided the feed wheel 57 having the knurled flanges 58 and 59 integral therewith. On the opposite end 90 of the shaft 56 is the ratchet wheel 60 by which the shaft is oscillated. To oscillate this ratchet wheel a lever 61 is provided loosely mounted on the shaft 56, having a pawl 62 thereon. To this lever is connected 95 a link 63 which in turn is connected to a lever 64 having a slotted end 65 therein, which lever is engaged by a pin 66, carried on a bell crank 67, pivotally mounted at 68 on a bracket 69. The bell crank 67 has a 100 slotted end 70 with which engages a pin 71 carried on the spacing bar 72, the end of which bar makes engagement with the mutilated periphery of the spacing wheel 73. The bar 72 is formed with a quarter turn as 105 is shown in Fig. 2. The mutilated periphery of the spacing wheel 73 determines the length of travel of the spacing bar 72 and this in turn through the levers, above described, determines the angular movement 110 of the ratchet wheel 60 operated by the pawl 62, and this in turn determines the angular movement of the feed wheel 57 for the purpose of advancing the check after an impression has been made thereon from 115 one type bar for the purpose of positioning the check to receive thereon the impression from another type bar, the feed being sufficient to carry the check along so that impressions made by one type bar will pre- 120 cede and be properly and evenly spaced from the impression made by the next type bar.

It will be understood that the type bars 125 will have words or characters thereon of different lengths and it is desirable to print a series of these in succession in a single line on the check and it is also desirable to have them uniformly spaced on the check and to secure this result it is necessary to 130

advance the check a distance equal to the length of character or word printed by a type bar plus the space desired between the characters and the type bar, and this feed 5 must be made for each type bar after the type bar has printed its impression on the check and to secure this so called irregular feeding of the check the spacing wheel and the feeding mechanism heretofore described 10 is provided.

The spacing wheel 73 is mounted to oscillate on a stud 74 mounted on a bracket 75 provided therefor. The spacing wheel is keyed to a gear wheel 76 which also is 15 mounted to oscillate on the stud 74, which gear wheel meshes with the gear wheel 77 keyed to the drum 28. The parts are so related that when a particular type bar is placed opposite the platen 30 the corresponding section of the periphery of the mutilated wheel 73 is presented to the spacing bar 72. It will be understood that there will be as many sections in the periphery of the spacing wheel 73 as there are type 20 bars on the belt 29, each having the same angular measurement. As the characters or words on the type bar increase or decrease in length, a correspondingly greater or smaller feed of the check is necessary. To 25 secure this a correspondingly longer or shorter stroke of the spacing bar 72 is necessary, which means that the spacing bar must approach correspondingly closer to or be stopped farther away from the center of 30 rotation of the spacing wheel 73. The more feed that is desired for the check the greater must the spacing wheel be cut away to correspond and the less feed that is desired for the check the less will the spacing wheel be 35 cut away for that particular type bar. If two adjacent type bars are provided with words or characters of equal length the corresponding section on the wheel 72 will occur in line with each other on the spacing 40 wheel or will appear as a single section of double length. If, after the spacing wheel is cut it is desired to change a single one of the type bars, making it shorter, the spacing wheel can be made to correspond by inserting a lug on that section of the spacing 45 wheel so as to make it correspondingly longer radially and decrease the travel of the spacing bar 72 to correspond. If a longer character is inserted the spacing wheel 50 must be cut away at the desired point to secure the properly increasing feed to correspond.

The spacing bar is moved into engagement with the spacing wheel on the downward 55 stroke of the handle 7 and the check is not advanced during that movement, but the pawl 62 is set with reference to the ratchet wheel 60 so as to secure the subsequent angular movement that is desired. The movement of the lever 32 is uniform and the

movement of the spacing bar is variable so that a rigid connection cannot be used to communicate the movement from the lever 32 to the bar 72. To provide for this variable movement of the spacing 60 bar 72 a spring is provided connected at one end to the lever 32 and at the other end to the lever 64. If the bar 72 can travel only a short distance the excess of up by stretching the spring accordingly. 75 While if the spacing bar 72 moves a long distance the spring 78 will be stretched only a small amount. The spring 78 will move the spacing bar in but one direction, which direction merely sets the feeding mechanism 80 and does not operate it. To move the spacing bar 72 in the opposite direction and move the feeding mechanism with it, a lever 79 is provided pivoted in the base plate. This lever has a slotted engagement with a 85 pin 72^a on the bar 72 to move the spacing bar to the right in Fig. 2. The lever 79 is operated from the lever 32 which engages with the lower end of the lever 79 during its upward movement, a certain amount of 90 lost motion existing between them, due to positions in which the lever 79 may be held on account of the irregularities of the spacing wheel. As the lever 79 is rocked to the right at the top, as shown in Fig. 2, it will 95 carry the spacing bar 72 with it in the reverse direction, which in turn will cause the pawl 62 to move and carry the ratchet wheel forward with it, also carrying with it the shaft 56 and the feed wheel 57 with its 100 knurled flanges 58 and 59.

The check moves through the machine from the shelf, forming part of the bed plate, marked "In" on one side of the machine to the shelf also forming part of the bed plate, marked "Out" on the other side of the machine, both of which shelves appear in Fig. 3. The knurled flanges 58 and 59 extend through the bed plate of the machine and the check is held in contact with the knurled flanges by means of a spring pressed roller 80 mounted on a lever 81 pivoted on the stud 82 provided therefor in the frame of the machine, a torsion spring 83 being provided around the stud 82 to hold the roller 80 in contact with the knurled flanges. The roller 80 is long enough to make engagement with both of the knurled flanges 58 and 59 so as to hold the check firmly in engagement therewith.

The mechanism of the machine above the bed plate is inclosed in a cover 84 which rests on the bed plate, being pivotally connected thereto at 85 so that it can be tipped up at the opposite end. The top of this cover is inclined and has a slot 86 therein through which extends a pointer 87 connected to the sprocket chain 15. A reading gage 88 is provided on the cover with which the pointer 125 cooperates for the purpose of indicating the 130

type bar that is placed above the platen 30. On the base plate of the machine is provided a check gage 89 which is adjustable forward or back for the purpose of holding the check 5 in proper alignment with reference to the platen.

The operation of my machine is as follows: The gage 89 is first adjusted according to the kind of check used. The roller 80 is raised and the check is placed in the correct position on the machine and the roller 80 is released to hold the check against the knurled flanges. The pointer 87 is then positioned to indicate the first character that it 10 is desired to print on the check. The handle 7 is then moved down which causes the platen to raise and press the check against the type bar indicated. The handle 7 is then raised which permits the feeding device 15 to operate and advance the check to the correct position to receive a new impression. The pointer 87 is then moved to the next character that it is desired to print on the check, after which the handle 7 is 20 again moved down and up. By repeating the foregoing series of operations any combination of characters can be printed on the check, all of which characters will be evenly 25 or uniformly spaced apart on the check.

30 The type bars are inked by inking rollers provided therefor as follows: A roller 90 is provided mounted on a bell crank 92 pivotally mounted on the stud 93, supported on a bracket 94. A spring 95 is provided fastened at one end to the frame of the machine 35 and at the other end to the short arm of the bell crank by which the inking roller is held in contact with the type bars. A similar roller 96 is mounted on a link 97 pivoted on 40 the stud 98, which stud is mounted on the frame of the machine. A torsion spring 99 is provided by which the inking roller is held in engagement with the type bars.

We claim:

45 1. In a machine of the character described, the combination of a belt comprising two flexible bands and a series of type bars secured thereto, two rotatably mounted drums over which said belt engages, means for rotating one of said drums, a platen with which any predetermined one of said type bars can coöperate, means for moving said platen against such type bar to impress a check held between them, projections formed 50 on and longitudinally of said type bars, and grooves formed in said drums for receiving said projections to cause the rotation of the other of said drums, each of said type bars being secured at points in its center line to said bands and tapered each side of such fastenings to permit the projection thereon being properly seated, to prevent a buckling of said bands and to properly center the selected type bar with respect to said 55 platen when in engagement therewith.

2. In a machine of the character described, the combination of a belt comprising two flexible bands and a series of type bars removably secured thereto, two rotatably mounted drums over which said belt engages, means for rotating one of said drums, a platen with which any predetermined one of said type bars can coöperate, means for moving said platen against such type bar to impress a check held between them, projections formed 70 on and longitudinally of said type bars, and corresponding grooves formed in said drums for receiving said projections to cause the rotation of the other of said drums, each of said type bars being removably secured at points in its center line to said bands and tapered each side of such fastenings to permit the projection thereon being properly seated, to prevent a buckling of said bands and to properly center the selected type bar with respect to said platen 75 when in engagement therewith.

3. In a machine of the character described, the combination of a movable means for selecting the word or character to be printed, a drum and means for rotating the same actuated by the movement of said selecting means, a shaft on which said drum is secured, a locking wheel secured to said shaft, a second drum, a belt engaging over said 80 drums and having a series of type bars thereon, a platen with which any predetermined one of said type bars can coöperate, means for moving said platen against such type bar to impress a check held between them, coöoperating engaging members on said belt and said drums for causing the rotation of said second drum, properly advancing said belt in either direction relative to the movement of said selecting means and centering the selected type bar with respect to said platen, a bar movable radially of and adapted to engage said locking wheel to center and lock such selected type bar during the printing 85 operation, and means for actuating said 90 bar.

4. In a machine of the character described, the combination of a movable means for selecting the word or character to be printed, a drum and means for rotating the same actuated by the movement of said selecting means, a shaft on which said drum is secured, a locking wheel secured on said shaft, a second drum, a belt engaging over said drums and having a series of 100 type bars thereon, a platen with which any predetermined one of said type bars can coöperate, means for moving said platen against such type bar to impress a check held between them, coöoperating engaging members on said belt and said drums for causing the rotation of said second drum, properly advancing said belt in either direction relative to the movement of said selecting 105 means and centering the selected type 110 bar.

bar with respect to said platen, a bar movable radially of and adapted to engage said locking wheel to center and lock such selected type bar during the printing operation, means for actuating said bar and means for moving the check a variable but predetermined distance longitudinally of said type bars after each printing operation.

5. In a machine of the character described, the combination of a series of movable type bars and a platen for engaging any predetermined one thereof, a pivotally mounted lever on one end of which said platen is secured and having a hole extending vertically through its opposite end, a shaft and means for oscillating the same, a crank keyed to said shaft, a rod pivotally connected at one end to said crank and extending through the opening in said lever, 10 a member longitudinally adjustable on said rod adapted to cause the actuation of said lever to raise the platen against the selected type bar, and resilient means for returning said lever to its normal or inoperative position and holding it in engagement with said adjustable member.

6. In a machine of the character described, the combination of a rotatable shaft having a drum and a locking wheel secured thereon, a series of type bars carried by and extending longitudinally of said drum, means for rotating said shaft to bring the selected type bar into operative position, a platen with which any one of said type bars can coöperate, means for moving said platen against such selected type bar to impress a check held between them, a bar supported to move radially of and to engage said locking wheel to center and lock the selected 20 type bar during the printing operation, a second shaft and means for oscillating the same, connections between said second shaft and said bar for actuating the bar, and additional means for returning said bar to its inoperative position.

7. In a machine of the character described, the combination of a rotatable shaft having a drum and a locking wheel secured thereon, a series of type bars carried by and extending longitudinally of said drum, means for rotating said shaft to bring the selected type bar into operative position, a platen with which any one of said type bars can coöperate, means for moving said platen against such selected type bar to impress a check held between them, a bar supported to move radially of and to engage said locking wheel to center and lock the selected type bar during the printing operation, a second shaft and means for oscillating the same, a cam on said second shaft, a pivotally mounted lever for actuating said bar, one end of such lever being pivotally connected to said bar and the opposite end engaging said cam, and a resilient connection

to said bar for returning the same to its inoperative position.

8. In a machine of the character described, the combination of a spacing wheel having a mutilated periphery, a bar movable 70 radially of the wheel adapted to engage with said periphery, a lever having a uniform travel, an elastic connection between said bar and said lever by which said bar is moved into engagement with the periphery 75 of said wheel on each operation of the lever, an endless type bar carrier geared to said spacing wheel and adapted to turn it and cause it to present different portions of its periphery to said bar to permit said bar to travel a greater or less distance on the operation of the printing device, a pivotally mounted lever engaging at one end with said first named lever and at its other end with said bar, such lever being actuated by the 80 return movement of such first named lever for returning said bar and causing the feeding of the check a distance proportioned to the travel of the bar.

9. In a machine of the character described, a spacing wheel having a mutilated periphery, a spacing bar supported to move radially of said wheel, means for rotating said wheel to bring different portions of its periphery opposite said bar, a lever having 90 a uniform travel, an elastic connection between said lever and said bar for moving the latter inwardly to engage the periphery of said spacing wheel during the movement in one direction of said lever, a second lever 95 pivotally mounted and having one end engaging said first named lever and its other end engaging said spacing bar, such lever actuated by said first named lever on the return movement thereof to move said spacing bar outwardly a distance equal to its inward movement, all for the purpose specified.

10. In a machine of the character described, a rotatably supported shaft and a ratchet wheel secured thereto, a spacing wheel having a mutilated periphery, a spacing bar supported to move radially of said wheel, means for rotating said wheel to bring different portions of its periphery opposite said bar, a lever having a uniform travel, a bell crank lever and a support therefor, one arm of such lever having slotted engagement with a pin on said bar, an elastic connection between said first 110 named lever and the other arm of said bell crank whereby said bell crank is actuated on the movement of said first named lever in one direction to move said bar inwardly to engage the periphery of said spacing 115 wheel, a third lever pivotally mounted and having one end engaging said first named lever and its other end having slotted engagement with a pin on said spacing bar, such lever actuated by said first named lever 120 125 130

on the return movement thereof to move said bar outwardly a distance equal to its inward movement, and connections between said bell crank and said ratchet wheel for imparting an angular rotation thereof corresponding to the movement of said spacing bar, all for the purpose specified.

11. In a machine of the character described, two sprocket wheels and a sprocket chain engaging thereover, a casing, a gage thereon, a slot in said casing, a pointer movable along said gage such pointer being secured to said chain and extending through said slot, a rotatable shaft and a drum secured thereon, gearing between one of said sprocket wheels and said drum for rotating the latter on the movement of said pointer in either direction, a second drum, a belt engaging over said drums comprising two flexible bands and a series of type bars secured thereto, a platen with which any predetermined one of said type bars can coöperate to impress a check held between them, coöperating engaging members on said type bars and said drums for causing the rotation of said second drum, properly advancing said type bars and centering the selected one with respect to said platen, a locking

wheel secured on said shaft, a locking bar movable radially of and adapted to make locking engagement with such wheel, a spacing wheel having a mutilated periphery and geared to one of said sprocket wheels, a spacing bar having a variable movement radially of such spacing wheel, means actuated by said spacing bar for feeding a check through the machine variable but predeterminable distances, a lever for moving said platen into operative position, an operating shaft, a handle secured thereto for imparting oscillatory movement to such shaft, means controlled by the movement of such shaft for moving said locking bar into operative position, additional means controlled thereby for operating said platen lever, and means actuated by the movement of said platen lever to cause the operation of said feeding bar.

In testimony whereof we affix our signatures in presence of two witnesses.

HERMAN C. WELTER.
CHAS. E. HALL.
